UNITED STATES PATENT OFFICE.

JOHN C. DUPEE, OF CHICAGO, ILLINOIS, ASSIGNOR OF ONE-HALF TO R. J. WHITE, OF SAME PLACE.

TINNER'S FURNACE.

SPECIFICATION forming part of Letters Patent No. 579,743, dated March 30, 1897.

Application filed November 14, 1896. Serial No. 612,084. (No model.)

To all whom it may concern:

Be it known that I, JOHN C. DUPEE, of Chicago, in the county of Cook and State of Illinois, have invented certain new and useful 5 Improvements in Tinner's Furnaces, of which the following is a full, clear, and exact description, reference being had to the accompanying drawings, forming a part of this specification, in which the corresponding letters of 10 reference in the different figures indicate like parts.

The object of my invention is to so construct a tinner's furnace that hydrocarbon oils, preferably of low gravity, may be advantageously 15 used therein without carbonizing and obstructing the burner or the passages leading thereto.

A further object is to so construct said burner that soldering-irons may be heated 20 therein without overheating the point and thus destroying or impairing the tin surface thereon.

To these ends my invention consists in the combination of elements hereinafter more 25 particularly described, and definitely pointed out in the claims.

In the drawings, Figure 1 is a vertical sectional view of my improved furnace, taken upon the line 1 1, Fig. 3, viewed in the direction of the arrow there shown. Fig. 2 is a like view taken upon the line 2 2, Fig. 3. Fig. 3 is a horizontal sectional view in plan taken upon the line 3 3, Fig. 1. Fig. 4 is an enlarged sectional view in detail taken upon the line 35 4 4, Fig. 3, showing a portion of the retort; and Fig. 5 is an enlarged rear view in detail of said retort or primary heating-chamber.

Referring to the drawings, *a* represents the usual oil tank or reservoir connected with 40 furnaces of this class, provided with any well-known opening for the reception of the oil, and a valve-controlled tube *b*, Figs. 1 and 2, with which is connected the ordinary flexible tube and bulb for forcing air into the reservoir.

A "T-union" *c*, Figs. 1 and 2, is tapped into the top of the reservoir and is provided with the usual needle-controlling valve, the stem *d* of which is extended, as shown, to the front 50 of the furnace. A short tube *e* is tapped into the top of the union *c* and into the bottom of

the retort *f*, which contains the primary heating-chamber hereinafter described.

The retort *f* consists of a hollow metal casting having the central opening *g* and the circular chamber *h*, communicating at the bottom with the tube *e* and closed at the top by means of a screw-plug *i*. The bottom of the retort is provided with an exterior screw-thread, by means of which a drip-cup *j* is attached. An elbow-shaped tube *k*, Figs. 2, 3, and 5, is tapped into the upper portion of the retort at its rear and is extended rearwardly and downwardly therefrom. A nipple *l*, Fig. 2, having a fine aperture therein, is located 65 in the lower end of said elbow concentrically with the opening *g*, so as to project a jet of vapor forward through said opening. Flanges *m*, Figs. 2, 3, and 5, project rearwardly from around the sides and top of the opening *g*, 70 while notches *n* are preferably formed therein for the admission of air in addition to that which may enter from the rear. An annular flange *o* is formed upon the part *f*, into which is fitted a cylinder *p*, consisting of two semi-cylindrical pieces having flanges *q*, Figs. 2 and 3, which serve to completely close the forward end of the cylinder as well as to attach the two halves together by means of the screw *r*. The interior of the cylinder *p* forms both 75 a mixing-chamber and primary combustion-chamber and is provided with a series of openings *s* at the sides, from which the flames may issue. A central stud *t* projects upwardly from the bottom of the mixing or primary 80 combustion chamber for the purpose of dividing the flame, as and for the purpose hereinafter described.

Extending laterally from the drip-cup *j* are arms *u*, which form a bracket or support for 90 a metal plate *v*, which is bolted thereto, as shown, and is curved upwardly at the sides and is preferably provided with flanges for the reception of a counterpart plate or shield *w*, the walls of the two being so curved at the 95 sides as to form an oval in cross-section, as clearly shown in Fig. 1. The part *w* is provided with a depending hood *x*, Figs. 2 and 3, which is extended below the elbow *k* and is adapted to shield the jet from the action 100 of cross-drafts of air. The space between the plates *v w* forms a secondary combustion or

heating chamber for heating soldering-irons, which are placed in said chamber in the manner indicated in dotted lines in Fig. 3.

The plate *v* is provided with openings near the front, as shown in Fig. 3, and openings *y* in the rear for the admission of air in such a way as to strike the point of the soldering-iron and prevent it from becoming overheated, while the plate or hood *w* is likewise provided with openings *z* at the rear, which, in effect, serves the purpose of a chimney. A shield *v'* beneath the secondary combustion-chamber serves to protect the reservoir from radiation.

Having thus described the various parts of my improved device, I will now explain its operation and point out its novel and improved features.

Air being forced into the reservoir, the valve-stem *d* is turned sufficiently to permit the oil to flow upwardly through the retort and issue from the nipple *l* into the drip-cup *j*. The oil is then lighted in the drip-cup in the usual manner for the purpose of heating the retort. As soon as the latter becomes sufficiently heated to partially vaporize the oil it issues from the nipple *l* in the form of a vaporized jet consisting partly of gas and partly of oil, which readily ignites the flame or jet passing through the opening *g*, and thus serving to heat the retort or chamber *h* to a temperature sufficiently high to partially vaporize the oil without causing it to carbonize and thus obstruct the passage. The jet then passes into the primary combustion or mixing chamber formed within the cylinder *p*, where it strikes the obstruction *t* and is divided and directed laterally toward the openings *s*, and being unable to escape at the forward end the flames are forced laterally and forwardly through said opening, as indicated by the arrows in Fig. 3. The flames being directed against the curved walls of the plates *v w* are directed thereby, as indicated by the arrows in Fig. 1, so as to meet at the middle above the cylinder *p*, against which the two flames are projected downwardly, as indicated, and caused to impinge upon the walls of the mixing-chamber, thus heating the latter to such a high temperature as to fully vaporize the oil. At the same time the air is admitted from the rear through the opening *g* into the mixing-chamber, where it commingles with the vaporous product of the oil at a temperature sufficiently high to enable the oxygen to form a chemical union therewith and produce complete combustion. As the tendency of the flames is to shoot forward from the mixing-chamber at about the angle indicated, they are, when brought together, caused to impinge upon the mixing-chamber, but not directly upon the retort, and inasmuch as air is admitted through the openings *y*, so as to impinge upon the retort, it follows that the latter derives most of its heat from the jet which issues from the nipple *l*.

It will be seen from the foregoing that the retort serves only to partially decompose the oil or to initiate its vaporization, but does not become sufficiently hot to cause carbonization, while the mixing-chamber is so formed as to constitute a primary combustion-chamber from which the flames issue to the main or heating chamber and react upon the mixing-chamber, thus completing the vaporization of the oil at the point of combustion instead of in an inclosure or passage devoid of air, and which would, therefore, soon become clogged as a result of carbonization.

Having thus described my invention, I claim—

1. A tinner's furnace in which are combined a source of oil-supply, a retort for heating and partially vaporizing the oil, a combined mixing and primary combustion chamber closed at its forward end and provided with an opening at its rear for the admission of air and openings at its sides for directing the flames into the heating-chamber, and a heating-chamber wholly or partially surrounding said mixing-chamber, the walls of said heating-chamber being so shaped as to direct the laterally-issuing flames and cause them to meet and impinge upon the mixing-chamber, substantially as described.

2. The combination in a furnace of the class described, of a source of oil-supply, a nipple in operative communication therewith, a retort interposed between said nipple and a source of oil-supply, and between said nipple and the mixing-chamber, a combined mixing and combustion chamber closed at its forward end, open at its rear end and having a series of openings at its sides, means for dividing the flame or jet from the nipple when introduced thereto and directing it forwardly and laterally from the side openings, and an outer heating-chamber extending over the top and having its side walls curved so as to cause the laterally-projected flames to meet and impinge upon the mixing-chamber, whereby complete combustion may be produced without causing the oil to carbonize in the retort, substantially as described.

3. The combination with a source of oil-supply of the retort *f* having a central opening and the circular chamber *h*, of the nipple *l*, in communication therewith and arranged in the rear thereof concentric with said opening, cylindrical mixing-chamber *p* closed at its forward end and provided with openings *s* at the sides, and a heating-chamber composed of the plates *v w*, having their side walls curved, substantially as described.

4. The combination in a furnace of the class described of a retort for heating the supplied oil to partial vaporization by means of a jet of flame directed through an opening in said retort, of a mixing-chamber arranged in operative proximity to said retort, means for introducing air thereto, means for causing the flame to issue laterally therefrom and an outer heating-chamber for directing the flame

back upon said mixing-chamber and openings in the rear of said heating-chamber for permitting air to be brought into contact with said retort and preventing the same from 5 becoming overheated, substantially as described.

In testimony whereof I have signed this

specification, in the presence of two subscribing witnesses, this 7th day of November, 1896.

JOHN C. DUPEE.
